US0D1087289S

(12) **United States Design Patent** (10) **Patent No.:** **US D1,087,289 S**
(45) **Date of Patent:** **** Aug. 5, 2025**

(54) **WATER SOFTENER**

(71) Applicant: **U&G Technology Co., Ltd.**, Incheon (KR)

(72) Inventor: **Sang Uk Kim**, Incheon (KR)

(73) Assignee: **U&G Technology Co., Ltd.**, Incheon (KR)

(**) Term: **15 Years**

(21) Appl. No.: **29/918,378**

(22) Filed: **Nov. 28, 2023**

(51) LOC (15) Cl. 23-01

(52) U.S. Cl.

USPC **D23/207**

(58) **Field of Classification Search**

CLAIM

The ornamental design for a water softener, as shown and described.

DESCRIPTION

FIG. 1 is a perspective view of a water softener showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is another perspective view of thereof.

(Continued)

The broken lines in FIGS. 1-8 depict portions of the water softener that form no part of the claimed design.

1 Claim, 8 Drawing Sheets
